UNITED STATES PATENT OFFICE.

HOUSTON M. CARROLL, SR., OF SAN ANTONIO, TEXAS.

WASHING-MACHINE.

1,379,851.

Specification of Letters Patent. Patented May 31, 1921.

Application filed January 26, 1921. Serial No. 440,079.

To all whom it may concern:

Be it known that I, HOUSTON M. CARROLL, Sr., a citizen of the United States, residing at San Antonio, in the county of Bexar and 5 State of Texas, have invented a new and useful Washing-Machine, of which the following is a specification.

This invention relates to washing machines, the primary object of the invention 10 being to provide a machine of this character which may be operated with the minimum amount of exertion on the part of the operator or by other powers, and one which will efficiently accomplish its purpose.

15 A further object of the invention is to provide a washing machine having a plunger, provided with means on one end thereof for forcing the articles under operation toward the ends of the body of the article- 20 holding receptacle, the means being such as will force the cleansing fluid through the articles.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawings:

35 Figure 1 is a plan view of a washing machine constructed in accordance with the present invention.

Fig. 2 is a cross sectional view taken on line 2—2 of Fig. 1.

40 Fig. 3 is a longitudinal sectional view taken on line 3—3 of Fig. 1.

Referring to the drawings in detail, the body of the receptacle includes a structure which is provided with a partitioning mem- 45 ber 6 disposed intermediate the ends thereof, dividing the structure into a tank 7 and a lever housing 8.

50 Rotatably supported between one end of the structure and the partitioning member 6, is an article receiving drum 9, which comprises opposed heads 10 and 11 respectively, which heads are connected by the spaced side members 12, which are provided with suitable openings 13 to permit fluid to pass 55 freely through the walls of the drum 9.

A relatively short shaft 14 has one end

thereof passing through one end of the tank wall, the opposite end thereof passing through the head 11, and through the bearing 15, which bearing is provided with an inner head to support the head 16 of the shaft 14 in spaced relation with the head 11.

As shown, the head 11 is cut away as 60 at 17 to provide a space between the head 11 and circular plate 18, which is provided with openings permitting fluid to pass to the space between the plate 18 and head 11, the edge of the plate being formed in a manner to present a circumferential flange 19 to guide the fluid in its passage from the 70 space.

The opposite head 10 is provided with a suitable opening registering with an opening in the partitioning member 6, which openings accommodate the plunger rod 20 75 that carries the plunger 21 on one end thereof, the plunger being in the form of a curved plate and provided with openings to permit the passage of fluid through the plate when the plunger is forced toward the opposite end of the tank 7.

This plunger 21 is dished in formation so that when the plunger is moved toward the head 10, a suction is created within the drum 9 to draw the fluid through the articles being washed and when the plunger is moved toward the head 11, the articles being washed are passed between the plunger 21 and plate 18 and the fluid thereby forced out of them, thus accomplishing the 90 cleansing thereof.

Operating within the housing 8 is an operating lever 22 which has its lower extremity pivotally connected to the housing, as at 23, the end thereof extending to a position 95 outside of the structure where the same may be readily and easily operated.

The rod 20 is pivotally connected to the lever 22 as at 24, whereby movement of the lever within the housing results in a relative movement of the rod 20 to move the same within the drum 9. The head 10 accommodates a portion of the flexible operating member 25, which is coiled around the head and secured thereto, one end of the 100 flexible operating member 25 passing over the pulley 26, the intermediate portion thereof being fastened to the lever 22, from where the same passes over the pulley 27 and over the pulley 28, which is supported 110 on the partitioning member 6.

Thus it will be seen that as the lever 22

is operated backward and forward, the flexible operating member 25 moves to revolve the drum 9 a predetermined distance in one direction, and move the drum in the 5 opposite direction and simultaneously cause the reciprocation of the plunger and plunger rod 20.

It might be further stated however that a portion of the drum 9 is hinged to provide 10 a cover for the drum and permit articles to be readily and easily inserted and removed.

It is believed that in view of the foregoing description a further detail description 15 of the operation of the device is unnecessary.

Having thus described the invention, what is claimed as new is:—

1. In a washing machine, a body portion, 20 a partitioning member within the body portion dividing the same into a tank and a lever housing, a rotatable drum supported within the tank, said drum having a plurality of openings formed in the wall thereof, 25 of, a lever pivotally supported within the lever housing, a plunger operating in the drum and having connection with the lever, means having connection with the lever and operating over the drum for rotating the 30 drum, and said plunger having openings formed therein.

2. In a washing machine, a body portion, 20 a partitioning member within the body portion for dividing the body portion into a

tank and a lever housing, a rotatable drum 35 supported within the tank, said drum including opposed heads, one of said heads having a cut away portion, a plate supported in spaced relation with the walls of the cut away portion, said plate having a 40 circumferential flange and having a plurality of openings, means operating within the drum for forcing fluid through the openings in the plate and into the space at the rear thereof, and means for rotating 45 the drum.

3. In a washing machine, a body portion, a partitioning member within the body portion, dividing the same into a tank and a lever housing, an article receiving drum rotatably mounted in said tank, said drum including opposed heads, spaced members connected to said heads and forming the sides of said drum, a lever pivotally supported within the lever housing, a flexible 55 member coiled around one of the heads of the drum and having connection with said lever to rotate the drum, and a plunger connected with said lever and operating through the partition and reciprocable with 60 said drum.

In testimony that I claim the foregoing as my own, I have hereto affixed my signature in the presence of two witnesses.

HOUSTON M. CARROLL, Sr.
